LAURITZ W. ANDERSEN, OF WATERBURY, CONNECTICUT

BOUQUET PIN

Application filed April 26, 1929. Serial No. 358,186.

This invention relates to a bouquet pin and has for its object to provide a pin which will hold a bouquet within itself by means of a clip secured to the bar portion, and the bar being so constructed that the point of the pin is protected.

A further object is to provide a pin for holding bouquets which is neat in appearance, inexpensive to manufacture and which will securely hold the bouquet together irrespective of whether the pin is secured to the article to which the bouquet is to be secured or not, and which will hold the bouquet securely in the position desired when attached to any fabric or material which may be pierced by the pin itself.

In the drawing Fig. 1 is a front elevation of the pin with a bouquet held thereby; Fig. 2 is a rear elevation of the pin with the prong broken away at the center to more clearly illustrate the clip member; Fig. 3 is a plan view of the pin with the stems of the bouquet which is held thereby in section; and Fig. 4 is a central transverse section through the pin on line 4—4 of Fig. 3.

The bouquet pin illustrated in the accompanying drawing shows one form of my invention and is composed of a relatively rigid metal bar member 10. At one end the bar is rolled back on itself to form a bearing 11 for the prong 12. The bearing portion 11 is provided with a transverse slot 13 at its center, the prong 12 being received in the slot with an end portion 14 which is bent at right angles thereto providing a pintle journaled in one end of the bearing 11. The side of the slot 13 opposite the bearing portion operates to hold the pintle portion 14 of the prong in its bearing.

The opposite end of the bar is bent back on itself at 15 to form a loop portion with the extreme end 16 directed toward but spaced slightly from the body portion of the bar, the end 16 being provided with a notch 17 to receive and hold the end of the prong. The loop portion 15 provides a guard for the point of the prong and prevents accidental catching or snagging of goods on the pin when in use.

The center portion 20 of the bar 10 is bowed

outwardly from the prong and in the center of the bow portion 20 is secured a resilient U-shaped clip 21 with its arms 22 shaped to receive the stems of a bouquet and hold them together. The outer free ends 23 of the arms 22 are bent outwardly back toward the bar so as to present smooth portions for contacting with the material to which the pin is secured and to provide a diverging receiving mouth for the clip through which the stems of the bouquet may be forced as they enter the holding portion of the clip. Stamped from each arm 22 is a prong 24 which projects inwardly across the mouth of the clip to engage the stems of the bouquet when forced into the clip.

In the pin shown, the bar 10 is stamped to provide a longitudinally depressed portion 25 in which the clip 21 seats. The side edges of the depressed portion prevent swiveling of the clip when secured to the bar by a single rivet 26, the stamped out portion also strengthens the bar longitudinally so that though made from very thin metal it is comparatively rigid. The bar 10 may of course be made in any shape desired and decorated in any appropriate manner.

It will be noted that the pin or prong 12 extends across the open end of the clip 21 so the material in which the pin may be fastened is held tightly against the clip thus aiding in holding the stems of the bouquet in place. The prongs 24 may, of course, be dispensed with, in which case the outer ends of the clip would be bent closer together to more nearly encircle the stems of the bouquet.

Having thus described my invention, what I claim is:

1. A bouquet pin comprising a bar member, a U-shaped clip secured at its center to the rear face of said bar, the outer ends of the arms of the clip being bent outwardly and toward the bar, to provide a stem receiving mouth on the clip and to present a smooth surface to the material on which the pin may be secured, and means at the rear face of the bar for securing it to a garment.

2. A bouquet pin comprising a bar member provided with an outwardly bowed seat

in the rear face thereof, a **U**-shaped clip at its center in the bowed portion of said bar, the outer ends of the clip being bent outwardly and toward the bar to present a smooth surface to the material on which the pin may be fastened, and means on the rear face of the bar for securing it to a garment.

3. A bouquet pin comprising a bar member provided with an outwardly bowed seat in the rear face thereof, **U**-shaped clip at its center in the bowed portion of said bar, the outer ends of the clip being bent outwardly and toward the bar to present a smooth surface to the material on which the pin may be fastened, a pin member hinged to the rear face of the bar and extending across the open end of said clip, whereby, when the pin is secured to a garment, the bouquet is held securely in the clip.

4. A bouquet pin comprising a bar member provided with an outwardly bowed seat in the rear face thereof, a **U**-shaped clip secured in said seat with the open portion extending rearwardly, a pin member pivoted to one end of said bar, the opposite end of the bar being bent rearwardly and inwardly and provided with a notch for receiving the point of said pin, said pin, when hooked in said notch, extending across the open end of said clip.

5. A bouquet pin comprising a bar member provided with an outwardly bowed seat in the rear face thereof, a **U**-shaped clip secured at its center in the bowed portion of said bar with its open end projecting rearwardly, the ends of said clip being bent outwardly and toward the bar, and prongs on the inner side of the arms of said clip for securely holding the stems of a bouquet when received in said clip, and means on the rear face of the bar for securing it to a garment.

6. A bouquet pin comprising a bar member provided with an outwardly bowed seat in the rear face thereof, a **U**-shaped clip secured at its center in the bowed portion of said bar with its open end projecting rearwardly, the ends of said clip being bent outwardly and toward the bar, and prongs on the inner side of the arms of said clip for securely holding the stems of a bouquet when received in said clip, said prongs being stamped from said clip, and means on the rear face of the bar for securing it to a garment.

7. A bouquet pin comprising a bar member having an outwardly bowed seat in the rear face thereof, a substantially **U**-shaped clip secured to the inner side of said bowed portion of said bar member, a single securing means for fastening said clip to said bowed portion, means on the inner side of said bowed portion for preventing relative movement of said clip along said bar, and

means at the rear face of said bar member for securing said pin to a garment.

8. A bouquet pin comprising a bar member having an outwardly bowed seat in the rear face thereof, a substantially **U**-shaped clip secured to the inner side of said bowed portion of said bar member, means for preventing relative movement of said clip along said bar member, and means in the rear face of said bar member for securing said pin to a garment.

9. A bouquet pin comprising a bar member having an outwardly bowed seat in the rear face thereof and provided with a longitudinally extending groove along its inner side, a substantially **U**-shaped clip secured to the inner side of said bowed portion of said bar member and adapted to fit into said grooved portion of said bar member for preventing relative movement of said clip along said bar member, and means at the rear of said bar member for securing said pin to a garment.

10. A bouquet pin comprising a bar member provided with an outwardly bowed seat at the rear face thereof, a substantially **U**-shaped clip secured at its center in the bowed portion of said bar, the outer ends of said clip being contoured to present a smooth surface on the material to which the pin may be fastened, and means on the rear face of the bar for securing it to a garment.

11. A bouquet pin comprising a bar member provided with an outwardly bowed seat at the rear face thereof, a substantially **U**-shaped clip secured to the bowed portion of said bar, the outer ends of said clip being bent outwardly and toward said bar to present a smooth surface to the material on which the pin may be fastened, a pin member secured to the rear face of said bar and extending across the open end of said clip whereby when the pin is secured to a garment the bouquet is held in said clip.

12. A bouquet pin comprising a bar member provided with an outwardly bowed seat in the rear face thereof, a substantially **U**-shaped clip secured to said seat with the open portion extending rearwardly, a pin member pivoted to one end of said bar, the opposite end of said bar extending beyond the point of said pin and being bent back around the point of said pin for providing a guard for said pin point.

13. A bouquet pin comprising a bar member provided with an outwardly bowed seat in the rear face thereof, a substantially **U**-shaped clip secured to the bowed portion of said bar member with its open end projecting rearwardly, the ends of said clip being bent outwardly toward the bar, means on the arms of said clip for securely holding the stems of a bouquet when received in said clip, and means on the rear face of the bar for securing it to a garment.

14. A bouquet pin comprising a bar member provided with an outwardly bowed seat in the rear face thereof having a longitudinally extending groove along its inner side, a U-shaped clip secured in said seat with the open portion extending rearwardly, said clip being adapted to fit into said grooved portion of said bar member for preventing relative movement of said clip along said bar member, one end of said bar member being bent rearwardly and inwardly and provided with a notch for receiving the point of said pin which when hooked in said notch extends across the open end of said clip, the other end of said bar member being pivoted to the rear face of said bar.

5 In testimony whereof, I hereunto affix my signature.
